United States Patent Office.

ELHANAN OMENSETTER, OF PHILADELPHIA, PENNSYLVANIA, ASSIGNOR
TO SAMUEL MACFERRAN, OF SAME PLACE.

Design No. 4,196, dated June 28, 1870.

DESIGN FOR RAILING.

The Schedule referred to in these Letters Patent and making part of the same

I, ELHANAN OMENSETTER, of the city of Philadelphia, and State of Pennsylvania, have invented and produced a new and original Design for Iron Railing, of which the following is a specification.

The nature of my design is fully represented in the accompanying photographic illustration, to which reference is made.

The photograph represents a side elevation of a panel of a fence, composed of longitudinal rails, A and A', and open pales B.

The straight rails A A' are connected with the pales B, by means of corresponding openings.

The pales are composed of scrolls *a* and leaves *b*, whose central openings, *d*, are of such form that when

the pales are placed together their contiguous portions unite in forming figures somewhat of violin form.

The lower ends of the pales have pendants, *e*. Their upper ends terminate with scrolls, *a*, and a crown-leaf, *f*. The rails A A' have ornamental bands *g*.

I claim as my invention—

The design for iron railing, as shown.

In testimony that the above is my invention, I have hereunto set my hand and affixed my seal this 23rd day of April, 1870.

ELHANAN OMENSETTER. [L. S.]
